UNITED STATES PATENT OFFICE.

ROBERT JONES, OF FORT ROUGE, WINNIPEG, CANADA.

PENCIL-HOLDER.

1,083,835.

Specification of Letters Patent.

Patented Jan. 6, 1914.

Application filed June 11, 1913. Serial No. 773,088

To all whom it may concern:

Be it known that I, ROBERT JONES, a subject of the King of Great Britain, residing at Fort Rouge, in the Province of Winnipeg, Dominion of Canada, have invented certain new and useful Improvements in Pencil-Holders; and I do hereby declare the following to be a full, clear, and exact description of the invention, such as will 10 enable others skilled in the art to which it appertains to make and use the same.

This invention relates to improvements in article attachers, and has particular reference to pencil holders.

15 One object of the invention is to improve the construction of the gripping means for supporting the pencil which means is capable of attachment preferably to a hat, but can be as readily attached to the clothing.

20 Other objects and advantages will be apparent from the following description when taken in connection with the accompanying drawings.

25 In the drawings: Figure 1 is a front perspective view of my improved pencil holder. Fig. 2 is a rear perspective view of the same.

Referring particularly to the accompanying drawings, 10 represents the base or support for the holder, which is preferably in 30 the form of a spread eagle, the notches 11 and 12, respectively, at the upper and lower portions of the wings being particularly adapted for supporting the pencil holding clip. To the rear of the base is secured a 35 suitable attaching means as a safety pin 13, by means of which the device may be readily attached to the clothing, or to a hat. The clip is formed preferably of a single endless piece of wire, and includes the vertical front 40 parallel portions 14 which are disposed against the front of the base, and the vertical parallel rear portions 15 which are secured in any suitable manner to the back or rear face of the base. Connecting the upper 45 ends of the members 14 and 15 are the curved portions 16, these portions engaging in the notches 11 at the upper portions of the wings of the base. The lower ends of the front members 14 are connected by a

transverse member 17, while the lower ends 50 of the rear members 15 extend forwardly beyond the base and in the notches 12 as indicated at 18, where they project forwardly between the members 14, over the transverse member 17 and beyond the front 55 of the base. The forward ends of the members 18 extend vertically in parallel relation as indicated at 19 and are connected by a transverse member 20.

The vertical members 14 are so disposed 60 that their lower ends are spaced a greater distance from the base than their upper ends and formed of resilient wire. The pencil is placed transversely of the members 14 and by engaging the thumb under the member 17 and pushing down on the pencil, the pencil will push back tightly clamped between the members 14 and 19. Attention is also called to the fact that the upper portions of the members 19 are curved inwardly 65 so that the pencil will be properly seated and prevented from being forced upwardly by the resilient members 14, this member 14 pressing the pencil tightly into the curved portions of the members 14. 70

75 What is claimed is:

A pencil holding device comprising a base plate having upper and lower notches, means carried by the rear of the base for attaching the same to a support, and a pencil holding 80 clip formed of a single endless piece of spring wire and including vertical front and rear portions disposed, respectively to the front and rear of the base, said rear members being rigidly secured to the rear of the 85 base, the lower ends of the front members being directed outwardly, the lower ends of the rear members extending forwardly beyond the front of the base and between the front members, and upwardly and inwardly 90 directed pencil holding members carried by said forwardly extending members.

In testimony whereof, I affix my signature, in the presence of two witnesses.

ROBERT JONES.
